UNITED STATES PATENT OFFICE.

HENRY D. BOSTOCK, OF JACKSONVILLE, FLORIDA.

ANNUNCIATOR.

1,081,885.

Specification of Letters Patent. Patented Dec. 16, 1913.

Application filed July 25, 1913. Serial No. 781,180.

To all whom it may concern:

Be it known that I, HENRY D. BOSTOCK, a citizen of the United States, residing at Jacksonville, in the county of Duval and 5 State of Florida, have invented new and useful Improvements in Annunciators, of which the following is a specification.

This invention relates to improvements in annunciators or indicators and has particular application to an annunciator for use on 10 street cars for advising the traveling public of the various way stations along the line of travel.

In carrying out the present invention, it 15 is my purpose to provide a device of the class described which will embody in its construction among other features a pair of drums suitably spaced apart and designed to carry a tape or strip of fabric bearing the 20 names of the different stations and adapted to be wound from one drum to the other, the drums being mounted upon shafts journaled in the end walls of the casing surrounding the same and having one of such end walls 25 formed in such manner that the bearings may be readily disassembled so that the drums may be removed from the casing when such is desired or necessary.

It is also my purpose to provide a 30 station indicator or annunciator which will embrace the desired features of simplicity, efficiency and durability, one which is dust-proof and waterproof and one which may be installed and maintained at a minimum expense and readily and conveniently operated by the conductor or motorman in charge 35 of the car or train as the case may be.

With the above and other objects in view, the invention consists in the construction, 40 combination and arrangement of parts hereinafter set forth in and falling within the scope of the claim.

In the accompanying drawings, Figure 1 is a view in front elevation of an annunciator constructed in accordance with the present invention. Fig. 2 is a view in side elevation thereof showing the construction of the side walls of the casing by means of which the drums may be removed. Fig. 3 50 is a transverse sectional view through the annunciator. Fig. 4 is a longitudinal sectional view therethrough. Fig. 5 is a detail perspective view of the guide rollers and the supports therefor removed from the 55 casing.

Referring now to the accompanying draw-

ings in detail, the numeral 1 designates a casing constructed of any suitable material and of any desired outline, preferably rectangular. The front wall of this casing is 60 provided with a hinged door 2 by means of which access may be had to the interior of the casing, and such door at a point approximately centrally thereof is provided with a transparent window or sight opening 3. 65 The casing is preferably ornamented in some suitable manner.

Journaled in horizontally alining bearings carried by the opposite side walls of the casing 1 are upper and lower shafts 4, 5, 70 each carrying, within the casing, a drum 6 and terminating beyond one end wall of the casing in a manipulating handle 7. Extending into the casing and carried by the rear wall thereof are blocks 8 spaced apart transversely of the casing and disposed between the shafts 4 and 5 and journaled in horizontally alining bearings carried by the blocks 8 are guide rollers 9 spaced apart vertically and disposed in a plane slightly in advance 75 of the plane of the drums 6.

The numeral 10 designates a tape or strip of fabric having the opposite ends thereof suitably fastened to and wrapped about the drums 6 on the upper and lower shafts and 80 the central portion thereof trained over the guide rollers 9 and this tape has printed thereon matter indicative of the stations passed by the car or train as the case may be.

In practice, the handle 7 of the lower 90 shaft 5 is grasped by the operator and the lower shaft rotated so as to wind the strip of fabric upon the lower drum, the names of the stations being visible to the occupants of the car or train through the sight opening 95 or window 3. On the return trip, the upper shaft is rotated by means of the respective handle and the direction of movement of the strip or tape reversed. Thus, the traveling public will be advised as to the next preceding station or stopping point.

In order that the shafts 4 and 5 carrying the drums may be readily removed from the bearings, as when it is desired to repair such shafts, one end wall of the casing above 105 each bearing therein is cut transversely to provide a removable section 11, the inner surface of each removable section being provided with braces 12, while the portion of the wall above each removable section carries a latching pin 13 adapted, when the sections are in wall formation to coöperate with

the braces 12 and hold the sections against accidental displacement. The upper edge of each removable section 11 and the corresponding edge of the remaining portion of 5 the wall is cut on an incline so as to facilitate removing and replacing of the sections.

From the foregoing description taken in connection with the accompanying drawings, the construction, mode of operation 10 and manner of employing my invention will be readily apparent. It will be seen that I have provided an annunciator or indicator which will be found especially useful on street cars and wherein the drums carrying 15 20 the indicating matter may be readily removed so that the indicia bearing strip may be removed or replaced.

I claim:

A station indicator comprising a casing, 20 shafts journaled in the opposite end walls of

said casing and spaced apart therein, drums upon said shafts, an indicia bearing strip wound about said drums and adapted to be moved from one onto the other, one end wall of said casing including removable sections 25 each disposed above one of the bearings of said shafts and having the upper edge thereof beveled downwardly and inwardly, the adjacent edge of the fixed portion of the wall being beveled to correspond with the 30 first-mentioned edge, and means for locking said sections against accidental displacement.

In testimony whereof I affix my signature in presence of two witnesses.

HENRY D. BOSTOCK.
